FOLDING MACHINE TIMING MECHANISM

Leo M. Kahn, New York, N. Y., assignor to The American Laundry Machinery Company, Norwood, Ohio, a corporation of Ohio

Original application September 22, 1939, Serial No. 296,059. Divided and this application November 27, 1940, Serial No. 367,411

11 Claims. (Cl. 270—61)

This invention relates to folding machines such as are used in laundries for folding towels, sheets and the like, and relates more specifically to the timing mechanism in such machines.

The folding machine timing mechanisms herein described are of the type which operates selectively in accordance with the length of the article which is fed into the machine, i. e., which folds the article in two, three, or four, according to its length.

In this general type of timer, the motions of the folding blades have been controlled by electric circuits which have been opened and closed by moving contacts. In a Mayer machine, these contacts moved with the same speed over varying paths with electrodes at various points thereof (see United States Patent No. 1,581,753). The movable contacts were magnetized buttons at all times gripped magnetically between the disks, two of which were of iron. A large portion of the time, including all periods when the machine was in operation and no articles were being fed into it, the buttons which were in contact with the disks were restrained from moving with them. The resulting friction between the disks and the buttons had serious consequences. The buttons became worn and would jamb. The heat of the friction destroyed the buttons' magnetism.

It is an object of this invention to provide a timer which utilizes movable contacts of the kind described above but which does not use magnetism and in which friction is reduced to the amount normally present in any machine; to provide such a timer in which the movable contacts are positively and mechanically moved along their paths; to provide such a timer in which there is relatively no friction between the movable contacts and the element which moves them, even while they are motionless and that element is moving.

For a fuller understanding of the nature and objects of the invention, reference should be had to the following detailed description, taken in connection with the accompanying drawing, in which:

Fig. 1 is a view in elevation, partly diagrammatic, of a modification of the aforesaid Mayer device;

Fig. 2 is a view in end elevation of the device shown in Fig. 1;

Fig. 3 is a view in cross-section, taken along the line 3—3 of Fig. 2, of a detail of the device shown in Fig. 1;

Fig. 4 is a view in elevation of a different form of the device shown in Fig. 1; and

Fig. 5 is a view of a detail of the device shown in Fig. 4.

It will be understood that the form of invention here disclosed is a modification or similar to the timing mechanism of the above mentioned Mayer patent and is intended to be utilized in a type of folding machine where the article to be folded travels along spaced tapes between which lies a measuring finger in the path of the moving article. The arrangement is such that the finger closes a contact, such as the switch 52 here disclosed, during that period of time required for the article to move over the finger. The timing mechanism is so set during the depression of this finger as to automatically operate a folding blade at an appropriate time transversely to the direction of movement of the article so as to lift the latter and present it to a pair of folding rolls. This folding mechanism is not here illustrated as it is well known in this art and is illustrated in the above mentioned Mayer patent.

The device shown in Figs. 1 to 5 is another form of the Mayer device in which there need be no magnetic disk and the contacts are not magnetic. They are each carried past the strips 106 by one of the supports 130 frictionally engaged and rotatable with shaft 102.

A support 130 comprises a pair of parallel rods 132 generally radial to shaft 102. Each contact 112 has a pair of passageways through which one pair of rods 132 lies or loosely passes. One of each pair of rods is in contact, as it moves about shaft 102, with an arcuate electrode 134. The other rod is similarly in contact with an arcuate electrode 136 of smaller radius. Each contact 112 contains a solenoid 138 which has connections 140 to the rods and which operates a toggle 142 for jamming the rods against the contact passages to fix the contact 112 radially. The independent, subsidiary, electric circuit for fixing a contact radially comprises main 144, conductor 145, electrode 136, rod 132, connector 146, solenoid 138, connector 148, rod 132, electrode 134, and main 143. When that circuit is open, the toggle is not in effect and the contact 112 is slidable along the rods 132.

There are brakes in electrodes 134 and 136 so that contacts which are moving around shaft 50 102 may have their jamming circuits closed (contacts 112 held radially in position) while the contacts which have not started around shaft 102 may have their jamming circuits open and hence be slidable radially. The end portion of 55 electrode 134 which is disconnected from the rest

of the electrode 134, is independently connected to main 144 by conductor 146 which may be broken at switch 148. The result of this arrangement is that when one of the rods 132 is in contact with 134, and when the switch is open, there is no current through solenoid 138 and the contact 112 is movable along those rods. At the same time, another contact 112 on a moving rod is held fixed on that rod by the activated solenoid. The area of the rods against electrodes 134 and 136 is large enough to bridge the breaks which are so close to starting position of the rods that one pair will have crossed the breaks before another pair has reached the starting position.

The operation of the device is as follows. An article on the folder passes and closes switch 52. This operates solenoids 54 which causes plunger 122 to press against constantly rotating wheel 123 thus causing the plunger to rise and push contact 112 toward shaft 102. Simultaneously, solenoid 54 opens switch 148, opening the circuit through solenoid 138 so that contact 112 is free to slide along its rods 132. When the article leaves switch 52, it opens again, causing plunger 122 to fall away from knob 150, freeing it, contact 112, and rods 132, which latter are connected frictionally with shaft 102, to rotate about shaft 102. Brush 152 of contact 112 is available to contact the strips 106 whereupon the various folding mechanisms are set in play as described in the aforesaid Mayer patent. While contact 112 is in contact with strips 106, the electrical circuit is through conductor 145, electrode 136, rod 132, electrode 134, the folder mechanisms and back to conductor 145. When the rods leave electrodes 134 and 136, the circuit through solenoid 138 is broken, toggle 142 is inoperative, and gravity pulls contact 112 back to its starting position.

Figs. 4 and 5 show a modification of the last described device wherein the jamming of the contact on the rod 132 is entirely mechanical. There is but one rod for each contact 212. Pivoted to contact 212 is an element 254 through which, and through the contact, the rod 132 extends loosely. A spring 256 between the contact and element 254 holds them in a position to bind against rod 132 whereby they are fixed against the rod. Plunger 122 has a cam surface 258 which pivots elements 254 against the action of spring 256. The contact and element are no longer bound against rod 132 and are free to be slid thereagainst by the force of plunger 122. A permanently positioned cam 228 similarly releases the bind between contact and element, after the contact has passed by electrodes 134, so that gravity may here too bring the contact back to its starting point at the end of rod 132.

This application is a division of my copending application Serial No. 296,059, filed September 22, 1939.

What I claim is:

1. The combination in a timing mechanism, with a rotary contact carrier and a support provided with fixed contacts adjacent the path of said carrier, of a contact button held mechanically and movably by said carrier, means for shifting said button along said carrier toward and from the axis thereof and into operative relation with certain of said fixed contacts, and electric means on said carrier for holding said button mechanically against said carrier.

2. The combination in a timing mechanism, with a rotary contact carrier and a support provided with fixed contacts adjacent the path of

said carrier, of a contact button held mechanically and movably by said carrier, and means for shifting said button along said carrier toward and from the axis thereof and into operative relation with certain of said fixed contacts, said carrier comprising rod-like means rotatable about one end thereof.

3. The combination in a timing mechanism with a rotary contact carrier and a support provided with fixed contacts adjacent the path of said carrier, of a contact button held mechanically and movably by said carrier, means for shifting said button along said carrier toward and from the axis thereof and into operative relation with certain of said fixed contacts, and releasable mechanical means for holding said button mechanically at any one of a plurality of points along said carrier.

4. The combination in a timing mechanism comprising a plurality of contact carriers which are longer than they are broad and which are rotatable about their respective ends, a support adjacent the paths of said carriers and provided with fixed contacts adjacent the path of said carrier, a plurality of contact buttons held respectively and mechanically and movably by said carriers, and means for shifting said buttons along said carriers and toward and from their axes and into operative relation with certain of said fixed contacts.

5. The combination in a timing mechanism having a contact carrier rotatable about an axis and having a support provided with fixed contacts adjacent the path of said carrier, of a contact button slidable along said carrier toward and from said axis and adapted to engage said fixed contacts, means for shifting said button along said carrier, and means for mechanically locking said button in various adjusted positions along said carrier.

6. The combination in a timing mechanism having a contact carrier rotatable about an axis and having a support provided with fixed contacts adjacent the path of said carrier, of a contact button slidable along said carrier toward and from said axis and adapted to engage said fixed contacts, means for shifting said button along said carrier, and electrically operated means for locking said button in various adjusted positions along said carrier.

7. The combination in a timing mechanism having a contact carrier rotatable about an axis and having a support provided with fixed contacts adjacent the path of said carrier, of a contact button slidable along said carrier toward and from said axis and adapted to engage said fixed contacts, means for shifting said button along said carrier, and spring actuated latch means for locking said button in various adjusted positions along said carrier.

8. The combination of claim 7, wherein said first named means is provided with means for releasing said latch means during said shifting operation.

9. The combination of claim 7, wherein fixed means is provided along the path of movement of said carrier for releasing said latch means.

10. The combination in a timing mechanism having a contact carrier rotatable about an axis and having a support provided with fixed contacts adjacent the path of said carrier, of a contact button slidable along said carrier toward and from said axis and adapted to engage said fixed contacts, means for shifting said button along said carrier, electrically operated means for lock-

ing said button in various adjusted positions along said carrier, and an electrical circuit including said carrier for energizing said last named means.

11. The combination in a timing mechanism having a contact carrier rotatable about an axis and having a support provided with fixed contacts adjacent the path of said carrier, of a contact button slidable along said carrier toward and from said axis and adapted to engage said

fixed contacts, means for shifting said button along said carrier, power operated means for locking said button in various adjusted positions along said carrier, an energizing circuit for said power means, and means for interrupting said circuit during operation of said button shifting means.
